United States Patent

Des. 238,786

Patented Feb. 10, 1976

238,786

CIRCUIT MOUNTING PACKAGE

David Nixon, Anaheim, and Thomas T. Chen, Yorba Linda, Calif., assignors to Rockwell International Corporation, El Segundo, Calif.

Filed Jan. 24, 1974, Ser. No. 436,304

Term of patent 14 years

Int. Cl. D13—03

U.S. Cl. D26—1 R

FIG. 1

FIG. 2

FIG. 3

FIG. 4

FIG. 1 is a perspective view of a circuit mounting package showing our new design.

FIG. 2 is a top plan view of the package with the top omitted for purposes of disclosure.

FIG. 3 is a bottom view of the same.

FIG. 4 is a side view of the invention as shown in FIG. 1.

The electrical conductors are shown in broken lines on the surface of the package in FIGS. 1, 2 and 3 for illustrative purposes only.

We claim:

The ornamental design for a circuit mounting package, as shown and described.
